UNITED STATES PATENT OFFICE

OSCAR O. OPPENLAENDER, OF ELIZABETHTON, AND RALPH H. CARTER, OF JOHNSON CITY, TENNESSEE, ASSIGNORS TO AMERICAN GLANZSTOFF CORPORATION, OF NEW YORK, N. Y., A CORPORATION OF DELAWARE

SEALING MEANS

Application filed August 20, 1931. Serial No. 558,310.

- Our invention relates to a liquid seal to be used in wash tanks, and more particularly to provide an effective seal between the bottom tier of spools and the openings in the tank.
- 5 One object of our invention is to construct a new type of acid resistant sealing means to be used in washing or treating tanks which will more effectively and efficiently produce those desirable results 10 which should be obtained in the washing of spools, having artificial threads or filaments or other threads or filaments wound thereon, by means of either a vacuum or pressure system.
- 15 Another object of our invention is to provide means which will effectively produce a seal between the washing or treating tank and the lowermost tier of spools so that, when a pressure or a vacuum washing system is 20 used there will be no leakage therebetween.
- A further object of our invention is to so construct a sealing means which will prevent any of the acid used in the washing or treating of the threads or any of the acid 25 adhering thereto from collecting around the sealing means and causing those threads on the lowermost tier of spools and also the spools to be damaged or otherwise rendered useless.
- 30 Other objects will become more apparent from a perusal of the following description and a study of the drawing in which:
- Figure 1 is a view in cross-section taken along lines 1—1 of Figure 2, showing the 35 annular sealing gasket or ring situated in the bottom of a washing or treating tank with a spool in position thereon; and
- Figure 2 is a top plan view of the sealing gasket or ring.
- 40 In the manufacture of artificial filaments or threads, it is customary, in certain processes, to collect the said filaments or threads upon a foraminated or perforated spool, and while thereon, to subject them to washing, 45 desulphurizing, deacidifying, bleaching, etc., treatments; such treatments being those usually included in the term "wet treatment." These spools carrying the yarn are placed in tiers in a suitable tank, each stack 50 of spools fitting around an opening in the tank. A cap is placed on the top spool of each stack and the filaments or threads undergo several treatments by either forcing the treating liquid through the foraminated or perforated spools and the layers of threads 55 or filaments, or by filling the tank with the treating liquid and by vacuum sucking the treating liquid through the layers and spool. The present invention has to do with a ring or gasket of novel construction by means 60 of which the bottom edge of a spool upon which the filaments or threads have been wound may be held liquid tight against the bottom of the tank in which the treating operations are to take place.
- 65 Referring now to Figure 1, we have shown the bottom 1 of a washing or treating tank 2. The tank is made of any suitable material, preferably steel, and the bottom thereof is lined with rubber or any suitable lining material 3. Provided at spaced intervals at the bottom of the tank are openings 4 which permit of communication with a vacuum or pressure means (not shown).
- 70 The annular sealing gasket or ring 5 comprises an annularly shaped member 6, formed preferably of hard rubber, and having a centrally depending cylindrical projection 11. A portion thereof is screw-threaded, as shown 75 at 12, while the end thereof is left smooth for a substantial distance whereby the tube 15 may be easily connected therewith. This tube makes a liquid-tight connection between the sealing means and the manifolds (not shown) which are located under the treating tanks.
- 80 Formed on the upper portion of the member 6 are a plurality of upstanding centering means or lugs 8 which are positioned inwardly from the periphery thereof. These lugs aid in the centering of the spools upon the gasket. These lugs, as well as the top portion of the gasket or ring, slope inwardly toward the center of the member 6 where there 85 is formed an opening or bore 7 and which extends through the projection 11 and communicates with the tube. It will readily be appreciated, that by this construction all of the treating liquid will be drained away,
- 90
- 95
- 100

thus effectively preventing the accumulation of any of the treating liquids around the bottom of the spool.

Cut or otherwise formed in the periphery of the ring 6 is a recess 9 which provides a seal 10 for a ring 14 made of soft rubber. This ring is vulcanized, cemented or otherwise secured in position and thus becomes, in effect, an integral portion of the gasket or ring. The periphery thereof is flush with the periphery of the hard rubber portion as is clearly shown in Figure 1.

To assemble the device a suitable sealing ring 13 is placed in the tank around an opening 4. The composite gasket is next placed in the tank, the portion 11 projecting through the opening being secured in place by means of any conventional locking means 18. A spool 16 is then positioned on the gasket and is accurately located in position by means of the lugs 8. The beaded edges 17 of the spool rest upon the soft rubber portion and due to the weight of the spool these edges are imbedded in the soft rubber. When suction or pressure is applied thereto, liquid is forced either inwardly or outwardly through the foraminated spool and through the filaments wound thereon.

From the above description it will be readily appreciated that there will be no leakage between the beaded edges of the spool and the soft rubber portion of the gasket. Thus there will be no loss of pressure or suction as the case may be.

It is understood that our invention is not limited to the precise construction shown, but that it includes within its purview whatever changes come within the terms or spirit of the appended claims.

Having now set forth our invention as required by the patent statutes, what we desire to claim is:

1. A sealing means for use in the liquid treatment of a tier of spools, including a circular base member upon which the bottom spool of the tier rests, a centrally formed bore in said base, a plurality of spaced upstanding spool centering lugs extending from the bore toward the periphery of the base member; the said lugs and the surfaces of the base member therebetween sloping downwardly from the periphery to the bore.

2. A sealing means for use in the liquid treatment of a tier of spools, including a circular base member embracing a sealing means upon which the bottom spool of the tier rests, a centrally formed bore in said base, a plurality of spaced upstanding spool centering lugs extending from the bore toward the periphery of the base member, the base portion being undercut with respect to the lugs to form a recess in which said sealing means rests; the said lugs and the surfaces of the base member therebetween sloping

downwardly from the periphery to the bore.

In testimony whereof we affix our signatures.

O. OPPENLAENDER.
RALPH H. CARTER.
